U. S. PATENT OFFICE.

No. 55.

1861.

WHOLE No. 1,420.

Cooking Stove.

GARRETTSON SMITH & HENRY BROWN, OF PHILADELPHIA, PENN.
ASSIGNORS TO LEIBRANDT & M'DOWELL, OF SAME PLACE.

Letters Patent for a Design No. 55, dated May 14, 1861.

SPECIFICATION.

TO ALL WHOM IT MAY CONCERN:

Be it known, that we, GARRETTSON SMITH and HENRY BROWN, of the city of Philadelphia, in the State of Pennsylvania, have invented or produced a new and original Design for the Plates of a Cooking Stove; and we do hereby declare that the following is a full and exact description of the same, reference being had to the annexed drawings, making a part of this specification, in which—

Figure 1 is a perspective view of the said stove, showing the front and side ornamentalations.

Figure 2, an elevation of the rear of the same showing the ornamentation on the back plate, and

Figures 3, 4, 5, transverse sections of the edge mouldings of the top and bottom plates and of the doors, respectively like letters when on the different figures indicating the same objects. Our invention or production consists of certain carved ornamentalations, on the plates constituting the front and side doors and the back plate, and of edge mouldings on the said doors and on the top and bottom plates respectively of a cooking stove, as hereinafter specified, which stove for the purpose of nominal distinction, we call "Live Oak". The ornamental figures in the middle of the two larger side doors, one of which is seen in figure 1 (and marked A,) and the ornamental figure B, in the middle of the back plate B' are alike, and are distinctly shown on the latter in figure 2. The ornamental figures in the middle of the two smaller side doors (one of which is seen in figure 1, and marked C,) and the ornamental figures in the middle of the two front doors D, D are alike and distinctly seen on the latter. The edge mouldings of

Smith and Brown's Design for a Cooking Stove.

each of the said doors (A, B, D, D,) are seen in perspective in figure 1, and in transverse section in figure 5.

The edge mouldings of the top plate E and bottom plate F, are seen distinctly in perspective, in figure 1, and also respectively in transverse section in figures 3 and 4. Each of the said ornamentalations constitutes part of its respective plate, and is therefore so carved in relief thereon as to readily admit of the patterns being drawn out of the sand, in moulding therefrom in the usual manner. What we claim herein as our invention or production and desire to secure by Letters Patent, is—

The described ornamental figure in the middle of each of the larger doors A, those in the middle of each of the two smaller doors C, and those in each of the two front doors D, and also the edge mouldings around the said doors A, C, D, the said mouldings being of the form or configuration shown in figures 1 and 5 respectively, also the described ornamental figure in the middle of the back plate B', and also the edge mouldings around the top plate E, and the bottom plate F, the said mouldings being, respectively, of the form or configuration shown in figures 1, 3, and 4, the said ornamentalations constituting a design for the plates of a cooking stove.

G. SMITH,
HENRY BROWN.
